F. H. GEORGE.
HATPIN PROTECTOR.
APPLICATION FILED JUNE 18, 1921.

1,425,194.

Patented Aug. 8, 1922.

UNITED STATES PATENT OFFICE.

FREDERICK HENRY GEORGE, OF WASHINGTON, DISTRICT OF COLUMBIA.

HATPIN PROTECTOR.

1,425,194.

specification of Letters Patent. Patented Aug. 8, 1922.

Application filed June 18, 1921. Serial No. 478,570.

To all whom it may concern:

Be it known that I, FREDERICK HENRY GEORGE, a subject of King of Great Britain, residing at Washington, District of Columbia, have invented certain new and useful 5 Improvements in Hatpin Protectors, of which the following is a specification.

My invention relates to improvements in hat pin point guards or protectors.

10 The invention has for its principal object to provide a device which when secured to either the inside or outside of the crown portion of a hat will readily receive and guard the pin point against excessive or 15 dangerous protrusion.

Another object is to provide a device which will securely grip the pin point and prevent accidental loss of the pin.

Other and further objects and advantages 20 of the invention will be in part described and in part obvious as the description is proceeded with.

In the accompanying drawings forming a part of this specification:

25 Figure 1 is a front fragmentary elevation of the inside of a hat crown showing the invention applied; and

30 Figure 2 is a top plan view of the invention partly broken away and partly in section, shown attached to the inside of a hat crown, the hat being shown in section.

Referring more particularly to the drawings, 1 denotes the inner wall or crown of a hat, secured to the inner face of which 35 is a flat strip or plate 2 of light sheet material, preferably fiber board. This strip 2 is fastened to the hat by means of small flat-headed bolts 3 and nuts 4 in an obvious manner.

40 Secured to the plate 2 is a preferably rectangular box like structure 6 formed with end flanges 17 adapted to receive any suitable fastening means such as rivets 5 or the like. The structure 6 which is preferably 45 made of light spring material is subdivided into funnel shaped compartments 7, having rectangular outer ends or mouths, the edges 8 of which are beveled or rounded to deflect the point of the pin 9.

50 The inner ends of the funnel shaped compartments 7 are formed with restricted openings 10 of sufficient size to permit slight

penetration of the pin point but prevent 55 passage of the shank of the pin therethrough. Means are provided in each compartment 7 for gripping the shank of the pin adjacent its point, comprising spring gripping fingers 11, cut from the walls of the compartments and pressed inwardly 60 therefrom towards a common center. Two or more such fingers will be provided each compartment.

In practice the user inserts the pin point 65 through one side of the crown of the hat, an eye (not shown) being preferably provided for this purpose, and thence across the opposite side of the hat crown, where the pin point will enter one of the funnel shaped compartments 7 and be guided into the restricted opening 10 thereof. The 70 spring gripping fingers 11 being curved at their outer or free ends, as illustrated in Figure 1, will assist in guiding the pin to the openings 10.

It has been determined by actual practice 75 that the user can readily project the pin point with sufficient accuracy to engage one of the openings 7, even though the latter be made much smaller and fewer in number than shown in the drawings.

80 The purpose of the strip or plate 2 is to prevent the pin point from being accidentally forced through and projected beyond the far wall of the crown of the hat. By making this plate or strip of comparatively soft 85 material such as fibre board the pin point will not be broken or blunted as would be the case if a metal plate were used.

Where my device is attached to a hat of 90 frail construction it may happen that in withdrawing the pin from engagement with the gripping springs the shape of the hat may be distorted. In order to prevent this, I provide a threaded knob 20 which may be 95 screwed into the hat from the outside and which may be grasped by the finger and thumb of the user for the purpose of resisting inward bending of the hat crown under stress incident to removal of the pin.

Having thus described my invention: 100

What I claim is:

A hat pin point protector comprising a box like structure of light spring material, the bottom wall of said box like structure

being extended to form fastening flanges, and means for securing said flanges to the crown of a hat, said box like structure being subdivided into funnel shaped compartments having restricted openings in their inner ends adapted to receive the pin point but prevent the passage of the pin there-

through, each compartment being formed with mouths of substantial area, the edges of the mouths being beveled, and gripping fingers pressed inwardly from the walls of each compartment.

In testimony whereof I affix my signature.
FREDERICK HENRY GEORGE.
